UNITED STATES PATENT OFFICE.

LEWIS E. STEWARD, OF MUNCIE, INDIANA.

FUSE FOR ELECTRIC CUT-OUTS.

1,080,496.

Specification of Letters Patent.

Patented Dec. 2, 1913.

Application filed December 10, 1912. Serial No. 735,989.

To all whom it may concern:

Be it known that I, LEWIS E. STEWARD, a citizen of the United States, residing at Muncie, in the county of Delaware and State of Indiana, have invented new and useful Improvements in Fuses for Electric Cut-Outs, of which the following is a specification.

This invention relates to fuses for electric cut-outs, and particularly to a novel construction and mode of mounting the fuse, the object of the invention being to provide a construction whereby, when the fuse burns out, a new fuse may be conveniently applied in its place.

A further object of the invention is to provide a fuse mounting which will permit of the escape of smoke and gases from the fuse casing when the fuse burns out, and which provides for the firm support of the fuse over the end caps of the fuse casing, to obviate liability of displacement of the parts.

The invention consists of the features of construction, combination and arrangement of parts hereinafter fully described and claimed, reference being had to the accompanying drawings, in which:—

Figure 1 is a longitudinal section through the fuse mounting. Fig. 2 is a longitudinal section taken at right angles to that shown in Fig. 1. Fig. 3 is an end elevation. Fig. 4 is a longitudinal section through the fuse strip and fuse terminals removed.

Referring to the drawing, 1 designates a tubular fuse casing, made of some suitable insulating material and closed at its ends by caps 2 and 3, secured in position by screws 4. The caps are adapted to be readily detached upon removal of the screws 4, and are respectively threaded to receive the terminal screws 5 and 6.

A fuse strip 7, of any suitable material, is arranged within the casing 1 and supported by terminals or bracket pieces 8. Each of these bracket pieces is approximately L-shaped, having a long arm 9, a short arm 10 arranged substantially at right angles thereto, and an offset portion 11 connecting said

arms. The ends of the fuse strip 7 are detachably connected with the longer inner arms 9 of said fuse terminal brackets by screws 12, while the short outer arms 10 of said fuse brackets are provided with threaded openings 13 to receive the shanks of the terminal or binding screws 5 and 6, whereby said terminals and fuse strip are supported in position within the casing.

It will be understood from the foregoing that in the event of the burning out of the fuse, the old fuse may be removed by first detaching one of the binding screws and its carrier cap and then detaching the other binding screw and its carrier cap, whereupon the destroyed fuse and fuse terminals may be removed from the casing and disconnected by detaching the screws 12, after which a new fuse strip may be connected with the terminals and the latter mounted therewith in the casing in an obvious manner.

It will be observed that the offset portion 7 of the fuse pieces adapts the fuse strip to be supported so that it lies in the plane of the screws 5 and 6 and centrally within the casing, the advantages of which will be apparent. The casing is provided with one or more vent openings 14 for the discharge of the smoke and gases upon the burning out of a fuse, thus preventing deposit upon the contained parts and avoiding liability of the inhalation of noxious gases by the party replacing the old fuse with a new one.

I claim:—

A fuse for electric cut-outs comprising a tubular open ended casing of insulated material having vent openings formed therein, end caps detachably secured to and closing the open ends of the casing, binding screws carried by said caps, substantially L-shaped fuse terminals disposed within the casing, each having its long arm extending longitudinally of the casing, and its short arm extending parallel with the adjacent cap and engaged and fastened thereto by the coacting binding screw, said long and short arms of each terminal being

connected by an offset arranged to dispose the long arm thereof in the plane of the binding screws, indent lugs upon the caps engaging the opposite sides of the short 5 arms of the terminals and holding said terminals from rotation, and a fuse strip detachably connected with the long arms of the fuse terminals and supported thereby

substantially in alinement with said binding screws.

10

In testimony whereof I affix my signature in presence of two witnesses.

LEWIS E. STEWARD.
